INVENTOR:

J. Dear Bonney,
by his Attorney,
Frederick Curtis.

United States Patent Office.

J. DEAN BONNEY, OF PEMBROKE, MASSACHUSETTS.

Letters Patent No. 66,291, dated July 2, 1867.

IMPROVED PAINT-BRUSH.

The Schedule referred to in these Letters Patent and making part of the same.

TO ALL TO WHOM THESE PRESENTS SHALL COME:

Be it known that I, J. DEAN BONNEY, of Pembroke, in the county of Plymouth, and State of Massachusetts, have invented a new and useful Improvement in the Manufacture of Paint-Brushes, and do hereby declare the following to be a full, clear, and exact description of the same, due reference being had to the accompanying drawings, making part of this specification, and in which—

Figure 1 is a side view of a paint-brush provided with my invention.

Figure 2 is a perspective view of a metallic strap of the invention to be hereinafter described; and

Figure 3, a perspective view of its confining-clasps.

Figure 4 is a transverse section of the brush with my invention applied.

This invention is an improvement in that class of paint-brush "heads" or clasps in which a metallic band is employed for confining the bristles and preventing their spreading out to an injurious extent.

The invention consists in a novel device for confining the metallic band and compressing it to any desired extent about the bristles, as well as in contracting the mouth of the head when thus surrounding the brush, and forming it with one or more corrugations, in a manner and for the purpose as hereinafter explained.

The object of this invention, besides producing the results above described, is to enable the same head or its confining-clasps to be used with a number of brushes, and for a great length of time, it being removed from a worn-out brush and applied to a new one, thus economizing its use and cost.

In the accompanying drawings, A denotes the mass of bristles or body of the brush, and a the handle thereof. B is a metallic band, which encompasses the bristles for about one-third their length, its edges being lapped over one another. The outer edge of this band B is formed with one or more corrugations b b, which has the double effect of strengthening and stiffening the head when the plate is bent into a circular shape, and of contracting the edge or mouth of such head about the body of bristles, for the purpose of preventing their spreading out to an extent to impair the efficiency of the brush, which would take place were the head of equal diameter from end to end. The band or head B is in turn encompassed by a metallic strap, C, having a lip, c, turned up on each end, at a slight angle to its sides, and at an acute angle to its periphery, for receiving a clasp, d, composed of a tapering strip of metal, with two lips formed upon its sides for extending over the ends of the strap C, the angle of the sides of the clasp d being the same as the ends of the strap C.

In applying my invention the band B is to be first passed around the brush, and its ends overlapped, and while held in this position is to be encompassed by the strap C, which is to be of such a length that its ends shall be separated by a small space, one about corresponding in size with the width of the clasp d. The larger end of the clasp d is then to be passed over the tips e e and pushed towards the bristles. This will draw the ends of the strap C together, and, as a consequence, contract the strap, and with it the band B very tightly and securely about the bristles.

After a brush containing the above-described device becomes worn out, the device may be removed and applied to a new brush with equal benefit. As it is comparatively indestructible, it may be applied to a great number of brushes.

Its utility and value will readily recommend themselves to painters, to whom it will chiefly be valuable.

I claim the combination, with the removable and adjustable metallic band which surrounds the bristles, of the clasp and its tapering slide for holding the said band upon the brush, substantially as and for the purposes set forth.
